UNITED STATES PATENT OFFICE.

HILDING F. PETERSON, OF MARSHALLTOWN, IOWA.

DESIGN FOR A SWING.

55,572.

Specification for Design. Patented June 29, 1920.

Application filed February 27, 1920. Serial No. 361,657. Term of patent 14 years.

To all whom it may concern:

Be it known that I, HILDING F. PETERSON, a citizen of the United States, residing at Marshalltown, in the county of Marshall and State of Iowa, have invented a new, original, and ornamental Design for a Swing, of which the following is a specification, reference being had to the accompanying drawing, forming part thereof.

Figure 1 is a side elevation of a swing, showing my new design;

Fig. 2 is an end elevation thereof.

I claim:

The ornamental design for a swing, as shown.

HILDING F. PETERSON.
